UNITED STATES PATENT OFFICE

GUSTAVE P. METZ, OF BAYSIDE, NEW YORK, ASSIGNOR TO H. A. METZ LABORATORIES, INC., OF NEW YORK, N. Y., A CORPORATION OF NEW YORK

RECEPTACLE FOR PACKING AMPULES

Application filed November 8, 1929. Serial No. 405,716.

The present invention relates to a receptacle for packing ampules; more particularly it relates to a receptacle for packing such ampules as are described, for instance, in U. S. Patents 1,699,305 and 1,713,854 of Felix Meyer. The said ampules are characterized by possessing at a certain place of their neck a local permanent tension of such form, course and intensity that this tension will not suffice to crack the glass at once or at an unintentional time, for instance, at a sudden change of temperature, but only when this crack is intentionally and wilfully caused by slightly injuring the skin or surface of the glass at any point of the part where the tension has been set up (compare page 1 of U. S. Patent 1,713,854).

The object of my invention is to provide the receptacle in which the ampules are to be packed, with a device capable of causing the cracking of the glass at the part where the tension has been set up, thus obviating the use of a special device for performing this feature. One way to accomplish this aim is to provide the box in which the ampules are to be packed, with a hole, the circumference of which is provided with a layer of carborundum, emery paper or a similar material being as hard or harder than glass, the said material being fixed to the cardboard by means of water glass or a similar adhesive material, and the diameter of the said hole being large enough to allow the neck of the ampule where the local permanent tension is set up, to come into contact with the abrasive substance applied to the circumference of the hole. By putting the neck of the ampule through this hole exercising a slight pressure against the abrasive surface and turning the ampule around the glass is caused to crack and the neck of the ampule breaks off easily.

One may also provide one edge of the box with a cut, for instance, in the shape of a V, the edge of the cut being likewise provided with a layer of carborundum or a similar material, fixed to the cardboard by means of water glass or a similar adhesive material.

The accompanying drawings give an illustration of my invention.

Fig. I shows a vertical section of the open

box (without cover), the compartments proper for the ampules being lifted up somewhat so that the ampules can be easily withdrawn.

Fig. II shows a vertical cross section of the open box (without cover), one line A—A' of Fig. I showing an ampule the neck of which is put through the hole.

Fig. III shows a sectional view of one side of the open box (without cover) being provided with a V shaped cut.

In Fig. I, No 1 designates a vertical side of my receptacle, No. 2 designates the hole, No. 3 the compartments containing the ampules, No. 4 shows that part of the ampules which is protruding from the compartments.

In Fig. II, No. 5 shows the side of the receptacle which is provided with the hole No. 2, 4 being the ampule, 6 being that part of the neck of the ampule which is capable of cracking when slightly injured.

In Fig. III, No. 7 designates a vertical side of my receptacle, No. 8 designating a V shaped cut the edge of which is provided with a layer of carborundum or a similar material.

It is understood that the aim of my invention can be accomplished in many other ways, my invention consisting mainly in the combination of the device for causing the breaking of the neck of the ampule with the packing box, thus obviating the use of two separate devices. I recognize that receptacles for packing ampules in the way as shown in my drawings are known to the art. Furthermore, it is known to scratch the surface of the neck of ampules by means of carborundum or other similar materials. I do not claim these features separately, but have limited my claims to the combination of both.

I claim:

1. A receptacle for packing such ampules as possess at a certain place a local permanent tension being sufficient to crack the glass by slightly injuring its surface, the said receptacle being provided with a hole in at least one of its sides, the circumference of the said hole being provided with a layer of a material being as hard or harder than glass and the diameter of the hole being so that that part of the ampule which possesses the local

permanent tension comes into contact with the abrasive substance applied to the periphery of the hole.

2. A receptacle for packing such ampules as possess at a certain place a local permanent tension being sufficient to crack the glass by slightly injuring its surface, the said receptacle being provided with a hole in at least one of its sides, the circumference of the said hole being covered with carborundum, and the hole being of such size as to receive and scratch that part of the ampule which possesses the local permanent tension.

3. A receptacle for packing ampules, the said receptacle having an aperture the edges of which are provided with an abrasive material as hard as or harder than glass rendering possible the injuring of the ampule at that part which is capable of cracking by the said injuring, the said aperture being of such size as to receive and scratch the part of the ampule to be cracked.

In testimony whereof, I affix my signature.
GUSTAVE P. METZ.
